UNITED STATES PATENT OFFICE

97,029

DESIGN FOR A SALT AND PEPPER RECEPTACLE OR SIMILAR ARTICLE

Richard M. West, Columbus, Ohio

Application July 18, 1935, Serial No. 57,720

Term of patent 7 years

To all whom it may concern:

Be it known that I, Richard M. West, a citizen of the United States, residing at Columbus, in the county of Franklin and State of Ohio, have invented a new, original, and ornamental Design for a Salt and Pepper Receptacle or Similar Article, of which the following is a specification, reference being had to the accompanying drawing, forming a part thereof.

Fig. 1 is a perspective view of a salt and pepper receptacle or similar article showing my new design;

Fig. 2 is a top plan view thereof;

Fig. 3 is a side elevational view.

I claim:

The ornamental design for a salt and pepper receptacle or similar article, as shown.

RICHARD M. WEST.
